VOLTAGE COMPENSATOR

Edwin Meyers Callender, Philadelphia, Pa., assignor to Edward G. Budd Manufacturing Company, Philadelphia, Pa., a corporation of Pennsylvania

Application April 19, 1943, Serial No. 483,606

7 Claims. (Cl. 171—119)

This invention relates to electrical control systems and it has particular relation to systems for automatically controlling the flow of power in a load circuit subject to line voltage variations.

In the copending application of Robert S. Phair, Serial No. 372,689, filed Dec. 31, 1940, now Patent No. 2,330,377 there is described a control system having particular applicability to electric resistance welding. As described in said application, resistance welding machines are frequently connected in blank to a single power source and at times the simultaneous draft of power causes a considerable voltage variation. Weld heat varies as the square of the current which in turn varies as the line voltage; hence, if welds are effected at such time, or at times when the line voltage is low for any other reason, these welds may be defective due to insufficient heat during the welding current flow. Manual means have not proven adequate for compensation of this line voltage variation.

It is an object of the present invention to improve the compensation for voltage change in electrical systems subject to important load and power variations. A further object is to provide correct compensation for instantaneous chopped line wave voltage drops peculiar to phase heat controlled resistance welding loads. Another object is to improve the electrical characteristics of the compensator control of the voltage of the peaking voltage transformer as used in welding circuits. More specifically, objects of the present invention are to improve in resistance welding the voltage compensation for variable current timer settings ranging from low to high current values; to reduce the distortion factor in the compensation under extremely heavy line voltage drops; and to reduce the normal current flow through the operating tubes of the compensator transformer circuit. Additional objects include increase in sensitivity and accuracy and such simplification of the control system as to reduce parts and costs.

The above and other objects of the invention, as will appear hereinafter, are effectuated by the control system detailed in the following description and described in the accompanying drawing in which:

Fig. 1 is a wiring diagram of the control circuits as applied to a resistance type welder;

Fig. 2 is a circle vector diagram illustrating a compared phase change arrangement;

Fig. 3 is a circle vector diagram illustrating a preferred phase change bridge arrangement; and

Fig. 4 is a diagram of the line voltage and load current during a welding cycle.

Referring to Fig. 1 of the drawing the numeral 10 designates the welding transformer having the primary coil 11 and secondary coil 12; the secondary including the welding electrodes 13.

The ignitrons 15 and 16 are of the conventional mercury pool type actuated by production of cathode spots in mercury 17 by the igniters 18 under impress of substantial voltage from the firing tubes 20 and 21. The anode 22 of the ignitron 15 is connected to the pool cathode 17 of the tube 16, and anode 23 of ignitron 16 is connected to cathode 17 of the other tube, to obtain the rectifying action of this inverse connection.

The firing tubes 20 and 21 are preferably of the tetrode type of gas filled tube or thyratron, the shield grids 24 having connection to the ignitron igniters 18 and the control grids 25 and 26 having connection to the peaking and hold-off transformers as will appear hereinafter. These tubes function to apply voltage on the ignitron excitors 18 when the negative voltage on the thyratron control grids is below a critical value, and at the same time a positive voltage is applied to the anodes 27, of these tubes.

Power is supplied the circuits from mains 28, tapers being made for the thyratron cathode transformers. The main circuit leads from points 29 and 30; from point 29 connecting the main to cathode 17 and anode 23 of ignitrons 15 and 16 and from point 30 connecting the other main to primary 11 and through the primary to the cathode 17 and anode 22 of ignitrons 16 and 15.

Connection is also made from the mains 28 to the hold-off transformer 35 having a primary 36 connected across the mains and secondaries 37, 38, 39 and 40, secondaries 37 and 39 as well as secondaries 38 and 40 forming units with coils of opposite polarity. One end of each of these units is connected to the shield grid of the firing tubes 20 and 21 as shown. The other ends are connected symmetrically through separate coils of the secondaries 41 and 42 of the peaking transformer 43 to the control grids 25 and 26 of the firing tubes as previously indicated. The primary coil 44 and saturable core 45 completes the transformer 43.

It is pointed out that the transformer assembly includes the coil 46 in operative connection with the welding time control unit (not shown), this coil also forming the primary of a transformer unit including the secondaries 39 and 40 of transformer 35.

The functioning of the transformer system described is as follows. Transformer 35 provides the necessary hold-off bias for the firing tubes 20 and 21. As is usual in resistance welding use is made of a variable portion of a given half cycle of current in accordance with the heat requirements of the particular weld. The length of time of weld application used is set by the timer connected to time transformer primary 46. The actual heating cycle is established by the peaking transformer 43 which by virtue of the

saturable core 45, develops a voltage wave of pronounced peak formation of sufficient value to impress a positive voltage on the firing tube control grids 25 and 26 above the critical value. This occurs when the timer primary 46 actuates secondaries 39 and 40 to neutralize secondaries 37 and 38 of transformer 35 thereby permitting the peaking transformer secondaries 41 and 42 to be effective on the firing tubes.

Under constant load and line conditions the above described circuits would be adequate for proper welding but under actual operative conditions both of these factors are subject to considerable variation. In order to compensate for such variations there is provided the phase change bridge and phase change compensatory control which will now be described. A phase change bridge circuit 49 is utilized comprising the fixed condenser 50 manually variable resistance 51, primary 52 of transformer 53, and adjustable resistance 54. The condenser 50 and variable resistance 51 are connected in series between points 55 and 56. Also between the same points the primary coil 52 and resistance 54 being connected in series-parallel. Connections to the main lines 18 are made at points 55 and 56. Also at points 57, between the condenser and variable resistance, and point 58, between the primary coil and fixed resistance, connection is made to the peaking transformer primary 44 through condenser 59, resistance 60, and choke coil 61.

It should be perceived at this point that with fixed phase relation between points 57 and 58 by virtue of rigid voltages developed between points 56 and 58 and also between points 58 and 55 of the bridge circuit a reduction of line voltage will cause a reduction in welding current in the welding secondary 12 thus tending to cause weld failure. This is because although the controlled ignition firing angle of the firing tubes 20 and 21 has not been changed, the magnitude of current passed by the ignitrons 15 and 16, being proportional to the voltage, will be reduced by the voltage line drop.

In order to overcome the above mentioned difficulties the inductance primary 52 of transformer 53 is made to function as a variable resistance under control of a circuit sensitive to line voltage changes and operative to vary this effective resistance in such a manner as to compensate both for line voltage and external load variations. To this end the secondary 70 of control transformer 53 is connected at its ends to the anodes of vacuum triode regulating tubes 71 and 72, the cathodes of which are interconnected. Likewise, the grids 73 and 74 of these tubes are interconnected, this circuit including resistances 75. Power for the tube filaments is supplied from the transformer 76 including the primary 77 and secondary 78, the mid-point of which is connected to the mid-point 69 of secondary 70 through variable resistance 79, or alternately directly to 69 as indicated by dotted line 111, the ends of secondary 78 having connection to the filament circuit of tubes 71 and 72 as shown.

A differential voltage, variable with line voltage, is applied to the grids 73 and 74 of tubes 71 and 72 by the following circuit. Direct current rectified from the power mains through transformer secondary 80, anode tube 81 and inductance filter 82-83, is passed through the adjustable potential potentiometer 84. One end 85, and the adjustable contact 86, of the potentiometer are connected to opposite points 87 and 88 of a

voltage reference bridge 89 having four bridge arms 88, 91, 92 and 93. Bridge arms 88 and 91 connected in series between points 89 and 100 include respectively in circuit the glow discharge voltage regulator tube 94 and fixed resistance 95. Bridge arms 92 and 93, in series between points 88 and 87 and in parallel with series circuit 88, 91, include respectively fixed resistance 96 and glow discharge voltage regulator tube 97. The glow discharge tubes are two element gas-diode tubes of the one way type having the positive electrode of area comparatively large with reference to the other electrode. The diode is designed to pass current at approximately 150 volts, this voltage remaining constant with varying impressed voltages. The resistances are designed to pass current which at normal line voltages gives a resistance voltage drop substantially the same as the diode tube. Thus, if a potentiometer or voltage divider as 102 be connected between points 89 and 100, between the diodes and resistance no current will flow under normal line voltage conditions. Should the line voltage be rectified and applied from variable voltage potentiometer 84 to bridge circuit terminals 88 and 87, be lowered, the voltage drop across resistances 95 and 96 will diminish and hence a voltage difference is effective at points 89 and 100. Utilization of this bridge voltage change is made by connecting the grids 73 and 74 of regulating tubes 71 and 72 to the movable arm 101 of a potentiometer 102 connected across bridge points 89 and 100; and by connecting the mid-point 69 of transformer secondary 70 to the movable arm 103 of potentiometer 104 connected across glow discharge tube 94.

The operation of the compensator circuit follows. Assuming functioning of the main power ignitrons, the timer and peaking transformer under normal load and line voltage conditions, the voltage drops in the reference voltage bridge 89 between points 87 and 88 and points 89 and 100 are approximately the same. Consequently the current in the anode circuit of transformer secondary 70 is low and at a value which establishes the normal cycle of the peaking transformer 43.

However, should there occur a drop in line voltage there would simultaneously occur a drop in the voltage of variable voltage potentiometer between points 86 and 85 which would at once establish a differential voltage on the reference voltage bridge at points 89 and 100, and impress a less negative potential on grids 73 and 74 of the regulating tubes 71 and 72. This lowers the effective resistance of the secondary 70 of the transformer 53 by increasing the anode current and disturbs the phase balance of the bridge 49, shifting the phase of the peaking transformer cycle to cause an earlier peak on succeeding cycles thus automatically lengthening the cyclic section of power application in the welding circuit.

Should the line voltage increase over the pre-established normal, a reverse action would follow, a more negative differential potential developing at reference bridge 89 to increase the negative potential between points 100 and 103 and at grids 73 and 74. In this manner the effective resistance of secondary 70 is increased causing a phase shift in the phase of the peaking transformer to delay the time of peaking, thus compensating for the increased line voltage. In brief whenever the line voltage drops the phase of the peaking transformer is advanced; and whenever the line voltage rises the phase of the peaking transformer is retarded.

An important feature of the invention will now

be described, reference being made to Figs. 2, 3 and 4 in this connection. Fig. 2 illustrates a voltage vector circle diagram in which the resistance 54 is directly connected to 0-angle point 55, and impedance 52 to point 56. With this arrangement of the bridge it is apparent that in order to increase the phase angle on the peaking transformer circuit with decrease in line voltage the effective resistance of impedance 52 must be increased. Hence, the electronic control of impedance 52 must be adapted to operate with increased current flow with a linear reduction on decrease in line voltage. This arrangement therefore normally requires appreciable current flow through the regulating tubes 71 and 72. Moreover, in resistance welding, on occurrence of abnormally heavy line voltage drops as indicated at 120, Fig. 4, the wave shape distortion factor increases in importance.

To improve the above mentioned factors the position of the inductance and resistance on the bridge circuit is reversed, as illustrated in Fig. 3, the impedance 52 now being connected to 0-angle point 56. Also by the regulating control as previously described, the effective resistance of impedance 52 is decreased with line voltage drop, thus securing the desired increase in phase angle. Additionally the regulating tubes 71, 72 are normally biased to give good wave form with a lower current value in the regulating tubes hence the distortion factor on the wave form is improved and the normal current consumption by tubes 71 and 72 is reduced.

Another advantage over the set-up of Fig. 2 is the improvement in compensation for all variations in timer heat settings. In Fig. 2 there is indicated by way of example a bridge arrangement where the voltage vectors of inductance 52 and resistance 54 are balanced at the mid-point 110. It is apparent from inspection that the angle a_3 for a given source voltage drop at high heat setting 119, of the resultant voltage vector 115 is less than the angle a_2 for medium heat setting 118 and for the same source voltage drop, a change opposite to that desired, since less compensation is required at lower heat and more compensation at higher heat.

To overcome this deficiency and to increase the compensation with increase in heat setting by substantially linear values, the connections of Fig. 3 are utilized and the junction point 58 shifted to the left of the mid-point. In other words, the bridge section 55—58—56 is unbalanced by adjusting resistor 104 connecting bridge 89 so as to reduce voltage drop on resistor 54 compared to that of coil 52.

With the unbalanced circuit as described, it is apparent from Fig. 3 that the angle a indicating shift of resultant vector 116 for decrease in source voltage to 130 increases as an approximately linear function of the heat setting for the same line voltage drop, with a maximum value at high heat 119. Also, for a uniform increase in line voltage to point 131 at the different heat setting, low 117, medium 118, and high 119, the phase angle b increases uniformly. Thus, by unbalancing the resistance-impedance bridge section as indicated the desired linear variation in compensation for varying heat settings is secured.

It is pointed out that the illustrations of Figs. 2 and 3 are diagrammatic, the actual unbalance being usually within ten per cent of the balance point, although on unusually high power factors

the unbalance is preferably increased, varying as high as 20%. Response on an I²T recorder indicates that with the described mode of compensation a uniform heat output is provided within 5% of optimum as against 30% for compensated circuits; and within 10% as against 70% for uncompensated circuits. This applies to low, medium and high loads. The described compensation with the indicated adjustments assures complete control of the heat output, and such adjustments as may be necessary are required only initially for all operating conditions, the subsequent compensation being entirely automatic.

The effectiveness of the described compensation system is indicated by shear pull tests where with a normal weld strength of 2250 lbs. for line drop with compensation, without compensation the weld strength was only 1350 lbs., this being far below normal.

In describing the control system emphasis has been laid on circuits and position of elements in said circuits. In general the electrical values of the electrical elements are not critical. However it is desirable that the resistance of resistor 54 in the phase change bridge 49 be appreciable, preferably over 3000 ohms. For operating voltage of 150 volts of the glow discharge diodes a value of ten thousand ohms is desirable in the resistances 85 and 98 of the reference bridge. Preferably ten thousand ohms in each of the grid circuits of regulator tubes 71 and 72 is desirable. The variable voltage potentiometer functions satisfactorily on ten thousand ohms. Values of forty thousand ohms and five hundred ohms are appropriate in potentiometer 84 and variable resistance 79. The reference bridge 102 in bridge 89 is normally set for zero voltage output and its swing on line voltage drop subtracts or adds to the voltage bias of resistance 104, usually within a range of 40 volts.

In preparing the described compensating equipment for use the contact 86 is adjusted on resistance 84 to obtain approximately a 300 volt drop between points 86 and 87 and a less than 5 volts drop between points 99 and 100, a zero reading being ideal. Then with a fixed heat setting 103 is adjusted on resistance 104 to give an alternating current voltage across bridge resistance 54 of about 240 volts. 101 is now set to midpoint on resistance 102, to be later more closely adjusted on ascertainment of the particular compensation requirement of the welding control panel.

It is pointed out that the reference voltage bridge 89 establishes a true proportion between the reference and variable voltages i. e. between points 99 and 100, the deviation depending only on the extent of variation of line source voltage from a normal assigned value. Consequently the range of compensation is enlarged, compensation being correctly maintained for large voltage changes of as high as 35% or even as high as 50% under some conditions of operation.

Another important factor in the phase control circuit is the utilization of the inductance input filter 82—83, which insures an output based on the average voltage occurring over the full voltage cycle.

Advantage is taken of a fast time constant for condenser 83 and resistor 84 so as to allow the direct current output voltage of the rectifier filter to follow closely all fluctuations of the line supply.

Consequently, at low heat settings in welder

operation occurring at over 90° in the voltage-time cycle, proper compensation is secured. This is an improvement over the capacitance type input filter which averages the input voltage only between 0° and 90° under ideal conditions and hence fails to average correctly the line voltage for low heat settings of the welding machine.

It is noted, also, that since the regulating tubes 71 and 72 are operated on alternating current it is desirable that self bias resistor 79 be used in conjunction with the direct current bias. This provides a refinement in tube operation that is not entirely essential and may be omitted where desirable by using the by-pass 11 indicated in dotted line.

Variations of the details of the invention may of course be made, the scope of the invention being determined and defined by the claims hereto appended.

What is claimed is:

1. An electric power transfer system comprising a load circuit, power supply electronic tubes, firing means for said power tubes, phase change means including an impedance for varying the firing point of said firing means, a source of alternating current voltage and control means for controlling the phase change means to compensate for source voltage change, said control means including electronic regulating grid-biased tubes connected to said impedance, means for rectifying said source voltage, means for establishing a fixed reference value of said rectified voltage and means for establishing a voltage in bridge relation to said reference voltage and variable directly with source voltage, said rectifying means averaging the full cycle variation of the transmitted source wave.

2. An electric power transfer system comprising a load circuit, power supply electronic tubes, firing means for said power tubes, phase change means including an impedance for varying the firing point of said firing means, a source of alternating current voltage and control means for controlling the phase change means to compensate for source voltage change, said control means including electronic regulating grid-biased tubes connecting to said impedance, and voltage means for decreasing the bias on the grids of said regulating tubes with decrease of source voltage, said voltage means including a voltage bridge circuit having fixed voltage branches, variable current branches and a bridge connected to the grids of said regulating tubes.

3. An electric power transfer system comprising a load circuit, power supply electronic tubes, firing means for said power tubes, phase change means including an impedance for varying the firing point of said firing means, a source of alternating current voltage and control means for controlling the phase change means to compensate for source voltage change, said control means including electronic regulating grid-biased tubes connected to said impedance, and voltage means for decreasing the bias on the grids of said regulating tubes with decrease of source voltage, said voltage means including a voltage bridge circuit having fixed voltage branches, variable current branches and a bridge connected to the grids of said regulating tubes, and a source of rectified voltage variable with source voltage connected to said voltage bridge circuit.

4. An electric power transfer system comprising a load circuit, power supply electronic tubes, firing means for said power tubes, phase change

means including an impedance for varying the firing point of said firing means, a source of alternating current voltage and control means for controlling the phase change means to compensate for source voltage change, said control means including electronic regulating grid-biased tubes connected to said impedance, and voltage means for decreasing the bias on the grids of said regulating tubes with decrease of source voltage, said voltage means including a source of rectified voltage variable directly with alternating source voltage, and a voltage bridge connected across said rectified voltage, said bridge comprising two parallel branches connected across said rectified

10 voltage, each branch having a constant voltage tube and resistance connected in series, but in inverse relationship, a bridge connecting the junction points of tube and resistance of each branch including a voltage divider and variable contact 15 means connecting said voltage divider to the grids of said regulating tubes.

5. In a welding circuit, a load, an alternating current voltage source, means for transmitting power from the source to the load, a phase change 20 means including an impedance for changing automatically the time of power transmission; and control means for controlling said phase change means, said control means comprising a potential bridge balanced for approximately zero potential 25 at normal source voltage, means for establishing a substantially constant voltage in said bridge, means for developing voltage on said bridge in direct ratio to source voltage change, resistance means for imparting resistance attributes to said 30 impedance, and circuit connections between said resistance means and said potential bridge.

6. In a welding circuit, a load, an alternating current voltage source, means for transmitting power from the source to the load, a phase change 40 means including an impedance for changing automatically the time of power transmission; and control means for controlling said phase change means, said control means comprising a potential bridge balanced for approximately zero potential 45 at normal source voltage, means for establishing substantially constant voltage in said bridge, means for developing voltage on said bridge in direct ratio to source voltage change, resistance means for imparting resistance attributes to said 50 impedance, including electronic tubes each having an anode and grid, and circuit connections between the tube anodes and said impedance and between the tube grids and said potential bridge.

7. In a welding circuit, a load, an alternating current voltage source, means for transmitting power from the source to the load, a phase change means including an impedance for changing automatically the time of power transmission; and control means for controlling said phase change means, said control means comprising a potential bridge balanced for approximately zero potential 60 at normal source voltage, means for establishing a substantially constant voltage in said bridge, means for developing voltage on said bridge in direct ratio to source voltage change, resistance means for imparting resistance attributes to said impedance, including two electronic tubes each having an anode and grid, said impedance being connected between said tube anodes, a connection between said tube grids and one side of said bridge and a connection between the other side of said bridge and the mid-point 65 of said impedance.

EDWIN MEYERS CALLENDER.
